CARBURETOR FOR INTERNAL COMBUSTION ENGINES

Ralph B. Hartsough, Los Angeles, Calif.

Application April 18, 1933, Serial No. 666,672

14 Claims. (Cl. 261—12)

This invention relates to means in a carburetor for automatically regulating the quantity, velocity and distribution of air used as a constituent of the explosive mixture, as such air approaches and enters the mixing chamber; and also for distributing the liquid fuel over extended surfaces in the path of the incoming air, such regulation being governed largely by engine speed, to cause vaporization of the fuel by the action of the incoming air automatically to secure with the most diverse kinds and grades of fuel, under all conditions of temperature, the most efficient mixture, while providing for optional heating of fuel, and also, optionally, for humidifying the fuel mixture under conditions making such steps of heating or humidifying or both desirable.

A principal object of my invention is to provide a carburetor which combines with the highest of efficiency and economy of operation (and such with any grade of fuel at all suitable for use with internal combustion engines) a reduction of manufacturing costs by elimination of parts and simplification of construction, resulting not only in a saving in the use of material, but also in permitting the most economical of manufacturing methods to be used in its production.

It is also an important object of the inventive subject-matter under consideration to provide a heating means for the incoming fuel (often desirable with certain grades of fuel or under certain conditions) and also (if desired) to furnish means for humidifying the fuel mixture, such optional heating and humidifying devices adding but slightly to the cost of manufacture of the carburetor and yet each being arranged and positioned for the most efficient performance of its respective function.

Another vital purpose of my said contribution to the art is to provide a carburetor which is most flexible in its adaptations to various motors, thus dispensing largely with a multitude of different sizes and designs to meet the requirements of engines of widely different constructions and capacities.

Other objects, qualities, advantages, and capabilities will be obvious to those of skill in this art from the following description, in which,—

Fig. 1 is a perspective view of the carburetor with optional auxiliary fuel pump and its conduit to the mixing chamber shown partially in section;

Fig. 2 is a longitudinal section through the principal portions of the carburetor;

Fig. 3 is a sectional view of the float-chamber on line 3—3 of Fig. 2;

Fig. 4 is an enlarged partly sectional and partly perspective view of the mixing chamber with air-inlet controlling means and the three annular chambers for, respectively, heating, humidifying, and fuel conveyance.

Considering in detail the drawings, the indicating numerals and letters of which refer to similar parts throughout the several views,—A indicates a fuel conduit from a source of supply such as a vacuum tank; B designates a float chamber (largely conventional in form, relative arrangement, and function, both as a whole and as to its separate parts); C indicates an adjusting needle valve for controlling the flow of fuel in its passage to the mixing chamber; D, the air and fuel mixing chamber; E, a spring controlled valve, regulating, in accordance with the requirements of the engine, the intake of air into the mixing chamber; F, an annular chamber for fuel supplied through ducts therefrom to the mixing chamber; G, an optional annular heating chamber (to contain either hot water from the cooling system or exhaust gases); H, an optional annular humidifying chamber; I, butterfly throttle valve controlling the flow of the explosive mixture to the engine.

Float 1 in float chamber B has attached to it one end of float lever 2 the opposite end of which is pivotally connected adjacent a wall of the cover of said float chamber B by pin 3 in a depending lug 4. 5 is a float valve of conventional form and arrangement adapted to be actuated by the leverage of said float lever 2 to open and close port 6 to regulate the flow of fuel into the float chamber, such being maintained at a constant level by the rise and fall of said float actuated lever in a manner well known to the art.

7 indicates a screen through which the fuel is required to pass on its way to the mixing chamber. 8 is a conduit for fuel leading from the bottom of float chamber beneath screen 7 through web 9 (which web connects float chamber B with the main body 10 of the carburetor). Passage through conduit 8 may be controlled by the movement of needle valve 11 to and from its seat 12, for the raising and lowering of which screw threads 13 are provided on valve stem 14, which is actuated in a quite obvious and well known manner, manually, by handle 15.

The annular chamber F is in open communication with conduit 8 and is so arranged that flow from the float chamber B will, in operation, keep

it normally filled with fuel. 16-16 indicate a series of ducts preferably spaced equidistant, extending through the wall of annular chamber F and opening as fuel conveying orifices into mixing chamber D of the carburetor.

Through boss 17 of valve cage 18, air-inlet control-valve stem 19 adjustably extends, said stem 19, being secured in said boss 17 by screw threads 20, nut 21 on the upper end of said valve stem 19, being provided for the locking of the same in any selected vertically adjusted position. Air-inlet control-valve 18 is in the form of a partially hollow truncated cone, vertically bored through its unhollowed part (forming its upper portion) to accommodate bearing-sleeve 22, which is swaged or otherwise secured into said bore of inlet-control valve E. Bearing-sleeve 22 is provided with shoulder 23 against which abuts spiral spring 24, which surrounds the lower portion of valve-stem 19, the lower end of said spiral spring 24 being confined and supported by a flange 25 on nut 26 which is screw-threaded to the end of valve-stem 19.

Annular chamber G is provided with an inlet opening 27 (Fig. 4) to which may be attached, if desired, any suitable conduit from exhaust manifold or water jacket of the engine, but which I have illustrated in the drawings, (Fig. 4) as being closed (inoperatively) by plug 28.

Annular chamber H is also provided with an inlet opening indicated at 29 (Fig. 2) to which may be attached, if desired, any suitable conduit for water, but which I have illustrated as being closed (inoperatively) by a plug 30. Through the inner wall of annular chamber H extends a series of (preferably equidistantly spaced) ducts 31, the same providing passage-ways for the injection of water, if desired, into mixing chamber D of the carburetor.

In Fig. 1 I have illustrated a form of fuel pump well known in the art, for accelerating purposes, consisting of cylinder 32 closed at its end 33, its opposite end being bored to receive a piston 35, which piston is adapted to reciprocate within the bore of said cylinder 32 for the purpose herein-after described. 36 indicates a compressible packing and 37 a gland, screw-threaded into the outer bore of said cylinder 32, said gland and packing being obvious and well known means for securing a tight sliding fit of said piston through the cylinder head.

Port 38 provides open communication between float chamber B (below screen 7) and cylinder 32. Tubing conduit 39 connects the interior of said cylinder 32 with annular chamber F. Link 40 is pivoted at one end of piston 35 and at its opposite end to link 41, the other end of link 41 in turn being pivoted to the carburetor casing at 42. Link 43 connects the toggle joint thus formed by the pivoted connection of links 40 and 41 to throttle lever 44, which by attachment to butterfly valve-stem 45 and by suitable connections (not shown) for the convenience of the operator, enables the manual manipulation of the butterfly valve controlling passage from the mixing chamber to the cylinders of the engine as well, coincidentally, of said accelerating device.

46 indicates generally intake connections for the conveyance of the explosive mixture to the engine cylinders (which latter forms no part of the present invention and which need not be further described).

The operation of the device, while perhaps obvious to those of skill in this art, will be briefly described: Air is drawn by the suction of

the engine into the carburetor mixing chamber D through the opening between the bars of valve cage 18, forcing air-inlet valve E downward against the tension of spiral spring 24 (which tension may be adjusted by manipulation of nut 26 at the bottom of valve-stem 19), such adjustment (through nut 26) as well also as that provided by the screw-threads and lock nut 21 at the top of valve-stem 19, also permitting a normal partly open position of said valve E as desired, while further opening in accordance with engine requirements as speed increased is provided for by the compressibility of spiral spring 24.

The fuel level (as governed by the float chamber 15 mechanism) when the engine is not in operation will be slightly below the orifice of ducts 16-16 into the mixing chamber, but will be raised in said ducts and drawn through the orifices thereof into said mixing chamber during the running of the motor. The multiplicity of said ducts 16-16 as well as their general design does not permit the fuel to be sprayed into the mixing chamber D but requires it to flow downward over the wall of the mixing chamber, where fine particles of vapor are taken off by the friction of the incoming air.

Heating chamber G is so positioned and designed with respect to annular fuel chamber F, and fuel inlet ducts 16-16, that most of the heat radiated from the wall of said heating chamber G is absorbed by the incoming fuel. Thus, the floor of said heating chamber G, constituting a partition, forming a large area enclosing the fuel stored for use in fuel chamber F, imparts a large proportion of its heat to said fuel; and as fuel inlet ducts 16-16 spread the incoming fuel out in slender threads in direct contact throughout their length with the heated walls of chamber D, a most efficient means is provided for heating the incoming fuel to any desired degree, thus to insure complete vaporization of even low grade fuel, the method of heating and the degree of temperature supplied to chamber G being easily devised, controlled and manipulated in accordance with means well known in the art.

The advantages of humidifying the fuel mixture under certain conditions are well known in the art, and the operation of the annular chamber F and its inlet ducts 31 need not further be described.

It will be understood that while in the foregoing illustrated description I have explained one embodiment of my invention, and have cataloged certain capabilities, uses and advantages inherent therein, I do not limit myself to the identical design, proportions or arrangement of the various parts, nor to the qualities, uses or advantages thereof, as I have partially attempted to outline them, as it will be quite obvious to all of skill in this art that the essence of my invention which I desire to secure by Letters Patent is capable of many modifications and of a construction in whole or in part in various and diverse forms.

What I claim and desire to secure by Letters Patent is:

1. In a downdraft carburetor, the combination of an annular fuel chamber surrounding a restricted air passage, said passage forming part of a mixing chamber, means to maintain a constant level of liquid fuel in said annular chamber, a series of conduits for said liquid fuel from said annular fuel chamber said conduits having

- orifices opening into said mixing chamber, a valve regulating flow of air through said restricted air passage, and a seat for said valve below the orifices of said conduits into said mixing chamber.
5. 2. In a downdraft carburetor, the combination of an annular heating chamber, an annular fuel supply chamber, an annular water chamber, each of said chambers having walls forming part of those of an air passage forming part of and 10 leading into a mixing chamber, conduits from, respectively, said annular fuel chamber and said water chamber opening into said air passage, conical means to restrict the bore of said air passage adjacent said conduits at all stages of acceleration of air therethrough and means to permit the automatic regulation of such restriction by the velocity of air, and means maintaining a constant level in said fuel chamber adjacent 15 to conduits therefrom into said air passage.
20. 3. In a carburetor, the combination of a plurality of annular chambers, each enclosing a space of different diameter from the others, said chambers being arranged with common partitions concentrically one above another, their inner walls respectively, forming segments of an air 25 passage Venturi opening into and forming part of a mixing chamber, a conduit from a source of liquid fuel supply to one of said chambers constituting a fuel supply chamber, a conduit from 30 a source of heat supply to another of said chambers constituting a heating chamber, a series of conduits from said fuel supply chamber into said air passage inclined in a direction opposite to that of the flow of air through said passage, a 35 valve controlling the flow of air into said air passage, and resilient means tending normally to actuate said valve toward closed position.
4. In a downdraft carburetor, a Venturi air 40 passage opening into a mixing chamber, the inner walls of which form partitions of a plurality of annular chambers surrounding said venturi, one of said annular chambers constituting a fuel supply chamber and having conduits through its walls into said Venturi passage, said conduits 45 having their openings into said Venturi passage so directed as to spread incoming fuel over said walls, a valve for controlling the flow of air through said air passage, resilient means tending normally to actuate said valve toward closed 50 position, and conduits to convey heat to the uppermost of said annular chambers for heating the fuel in said fuel supply chamber.
5. In a carburetor, the combination of three annular chambers arranged co-axially one above 55 another, the inner wall of each of said annular chambers, respectively, enclosing a space of different diameter from each of the others, said inner wall of each of said annular chambers forming a segment of the walls of a Venturi tube 60 air passage into a mixing chamber, one of said annular chambers constituting a water chamber having conduits therefrom into said air passage, another of said annular chambers constituting a fuel supply chamber having conduits therefrom 65 into said air passage, the third of said annular chambers constituting a heating chamber, and a valve controlling the flow of air through said air passage.
6. In a downdraft carburetor, a fuel mixing 70 chamber having walls forming a Venturi passage therethrough, a fixed member above said chamber, a resiliently actuated valve supported by said member to slide axially within said Venturi passage to regulate the area thereof, there being in 75 said Venturi walls fuel passages opening into said

mixing chamber nearest the chamber intake, the portion of the chamber below said valve being clear and unobstructed.

7. In a downdraft carburetor, a fuel mixing chamber having walls forming a venturi there-through, an air intake port, a stem axially positioned in the intake port of said chamber, and a resiliently actuated valve axially slidable on said stem to regulate the area of said venturi, there being in the walls of the venturi fuel passages 10 opening into said mixing chamber nearest said air inlet port, the portion of the mixing chamber below said valve being clear and unobstructed.

8. In a downdraft carburetor, a fuel mixing chamber having walls forming a venturi there-through, an air intake port, a stem axially positioned in the intake port of said chamber, and a resiliently actuated valve axially slidable on said stem to regulate the area of said venturi, there being in the walls of the venturi upwardly 15 directed fuel passages opening into said mixing chamber nearest said air inlet port, the portion of the mixing chamber below said valve being clear and unobstructed.

9. In a downdraft carburetor, a cylindrical 20 mixing chamber, a substantially conical sleeve seated therein to form a Venturi passage having its greatest restriction at the chamber intake port, said sleeve having passages for fuel into the mixing chamber near the intake end thereof, a stem axially extending into said Venturi passage, and a resiliently actuated conical valve axially slidable on said stem to regulate the area of said Venturi 25 passage, the mixing chamber below said sleeve being clear and unobstructed.

10. In a downdraft carburetor, a cylindrical mixing chamber, a substantially conical sleeve seated therein to form a Venturi passage having its greatest restriction at the chamber intake 30 port, said sleeve having upwardly and inwardly 35 directed passages for fuel into the mixing chamber near the intake end thereof, a stem axially extending into said Venturi passage, and a resiliently actuated conical valve axially slidable on 40 said stem to regulate the area of said Venturi 45 passage, the mixing chamber below said sleeve being clear and unobstructed.

11. In a downdraft carburetor having a fuel mixing chamber, means seated in said chamber to form a Venturi passage, there being fuel conduits through said means opening into said passage near the intake end thereof to cause liquid fuel from said conduits to sink down along and to spread out along the widening surface of said means in the path of the incoming air, and a valve adapted to regulate the velocity of air adjacent said means, there being within said means a space through which to pass a fluid for heating said means adjacent said fuel conduit openings.

12. In a downdraft carburetor having a fuel mixing chamber, means seated in said chamber to form a Venturi passage, there being fuel conduits through said means opening into said passage near the intake end thereof to cause liquid fuel from said conduits to sink down along and to spread out along the widening surface of said means in the path of the incoming air, and a valve adapted to regulate the velocity of air adjacent said means, there being within said means a space through which to pass a fluid for heating said means adjacent said fuel conduit openings, the said means being provided with a second space having passages into the mixing chamber for a humidifying liquid.

13. In a downdraft carburetor, a cylindrical fuel mixing chamber, a stem mounted above said chamber, said stem axially extending therein and being axially adjustable, a member seated at the top of the chamber to form a Venturi passage there-through, a conical valve slideable on said stem, and a spring urging said valve upward to close said passage, there being in said member upwardly directed conduits for fuel to the upper portion of said Venturi passage.
14. In a downdraft carburetor having a fuel

mixing chamber, means seated in said chamber to form a Venturi passage, there being fuel conduits through said means opening into said passage near the intake end thereof to cause liquid fuel from said conduits to sink down along and to spread out along the widening surface of said means in the path of the incoming air, and axially adjustable stem, a valve axially movable on said stem, and means yieldingly elevating said valve to regulate the area of said Venturi passage. 10

RALPH B. HARTSOUGH.
